CHEST

Kenneth V. Dobson, 3135 W. 1st Ave.,
Denver, Colo. 80219

Filed May 31, 1966, Ser. No. 2,473

Term of patent 7 years

(Cl. D33—6)

FIG. 1

FIG. 4

FIG. 2

FIG. 3

FIGURE 1 is a perspective view of the chest with the drawers in their various positions showing my new design;

FIGURE 2 is a top view thereof showing the various positions of each drawer;

FIGURE 3 is a bottom view of the chest; and

FIGURE 4 is a side elevational view of one of the four identical sides.

I claim:

The ornamental design for a chest, as shown.
